ABSTRACT

An extremely shallow flash socket assembly for use in or with a photographic camera is constructed to receive a multilamp flash assembly having at least one array of lamps facing in a common direction and a thin, shallow connector blade adapted to be inserted into the socket assembly. The socket assembly includes novel electrical interfacing structures including a stationary set of resilient contact members constructed and arranged to register with and to engage terminals on a connector blade inserted into the socket assembly. Novel features of the electrical interfacing system and cooperating socket structures are disclosed.

FLASH SOCKET ASSEMBLY

BACKGROUND OF THE DISCLOSURE

A new generation of photographic cameras has been revealed by the assignee of this application in recently issued patents, including U.S. Pat. Nos. 3,447,437; 3,543,662; 3,561,339; and 3,587,426. These patents disclose advanced folding cameras having an extremely high degree of compactness when in their folded state.

This invention concerns, in general, certain aspects of a novel flash illumination system having broad application but intended especially for use in or with such advanced cameras. The system utilizes as its source of luminous energy a disposable multilamp flash assembly having at least one, but preferably two, arrays of lamps of common orientation, as shown and described for example, in U.S. Pat. Nos. 3,598,984 and 3,598,985. In this flash illumination system, the flash assembly is interfaced with a flash selecting system which selects the flash lamp or lamps to be fired when a firing command is received. The flash selecting system is preferably a static electronic flash selecting circuit as shown, for example, in U.S. Pat. No. 3,618,492, assigned to the assignee of this invention.

As shown in the referent U.S. Pat. Nos. 3,598,984 and 3,598,985, the multilamp flash assembly includes a support structure from which extends a shallow, thin connector blade carrying a set of electrical terminals for the lamps. The flash assembly has two back-to-back arrays of lamps having respective sets of terminal strips disposed on opposite sides of the connector blade. The arrays are used in sequence by first igniting the lamps in one array, then disconnecting the flash assembly from the associated flash socket, reversing the orientation of the assembly, and reconnecting the assembly in the flash socket.

This invention is particularly directed to the provision of means for electrically interfacing such a multilamp flash assembly with a flash selecting system in or associated with a photographic camera, especially with a static electronic flash selecting circuit in an ultra-compact camera as above-discussed. The electrical interfacing is accomplished according to this invention in a novel flash socket assembly. Because of the extreme compactness of the described advanced cameras when folded, the total space available for the flash selecting system and for the means for making the electrical interconnections between the flash lamp terminals on the flash assembly and the flash selecting system is very small.

The requirements imposed upon the electrical interfacing system are, in general, very stringent and particularly so as compounded by the extreme limitation in available space. In a very restricted space, the electrical interfacing structures must: (1) insure electrical isolation of the individual contacts which engage the terminals on the connector blade of a flash assembly; (2) insure accurate registration of the contacts and lamp terminals such that the appropriate lamp terminal and no other is engaged by each contact; (3) preclude any possible simultaneous engagement of a contact with more than one lamp terminal; (4) insure the electrical integrity of the contact-terminal interfaces; (5) prevent any possibility that a lamp on the back of the flash assembly might inadvertently be ignited in the face of a user; (6) provide for thousands of flash assembly insertions and withdrawals without damage to the electrical contacts;

and (7) insure against overstressing of the contacts by the connector blade of a flash assembly.

The flash selecting system discussed briefly above has a resistance monitoring capability designed to detect a defective lamp of the type characterized by an abnormally low resistance. If the resistance of a lamp having priority for ignition is sensed to have a value below a predetermined minimum value, the flash selecting system recognizes this condition as indicative of a faulty lamp and will avoid that lamp. It is thus also extremely important that the distributed resistance in the electrical interfacing system which connects the flash selecting system with the lamps in the flash lamp assembly be very low so as not to interfere with the operation of such flash selecting systems.

OBJECTS OF THE INVENTION

It is a general object of this invention to provide an improved flash socket assembly for use in a photographic flash illumination system which employs as its source of luminous energy a disposable multilamp flash assembly having at least one array of lamps of common orientation and which includes a flash selecting control center which selects the lamp or lamps to be ignited when a firing command is given.

It is a less general object to provide such a socket assembly having means for electrically interfacing the flash assembly with the socket assembly which meets and overcomes each of the above-discussed constraints and design requirements.

It is another object to provide improved electrical interfacing means which occupies very little space in an associated camera, and which is capable, by virtue of its extreme compactness of being accommodated in an ultra-compact camera.

It is still another object to provide a flash socket assembly including a plurality of contact members, the socket assembly and contact members being constructed and arranged such as to substantially eliminate the possibility that a non-selected lamp might be ignited as a result of misregistration of a contact member with the associated terminals on the connector blade of a flash assembly. It is another object to preclude inadvertent ignition of a plurality of lamps as might result from simultaneous engagement of a contact member with more than one terminal.

It is yet another object to provide an electrical interfacing system for use in a flash socket assembly which insures a sound electrical engagement with and only with the forwardly facing terminals on the connector blade of a connected flash assembly; it is a further object to provide an electrical interfacing system which is durable and reliable.

It is another object to provide an electrical interfacing system which has a very low distributed resistance so as not to interfere with the operation of a camera's flash selecting system.

It is another significant object of this invention to provide such a flash socket assembly having structures for insuring the electrical isolation and accurate positioning of the electrical contacts contained in the assembly.

It is also an object to provide an electrical interfacing system for use in a flash socket assembly including a plurality of contact members for engaging the connector blade of a flash assembly, the contact members being constructed and arranged such that the force re-

quired to insert the flash assembly into the socket assembly is less than the force required to withdraw the flash assembly.

It is still another object to provide an electrical interfacing system having a plurality of contact members which exert a loading force on the connector blade of a flash assembly sufficiently great to retain the flash assembly securely in the socket assembly, and yet which are relatively resistant to overstressing.

Further objects and advantages of the invention will in part be obvious and will in part become apparent as the following description proceeds. The features of novelty which characterize the invention will be pointed out with particularity in the claims annexed to and forming a part of this specification.

BRIEF DESCRIPTION OF THE DRAWINGS:

FIG. 1 is a perspective view of the front portion of a photographic camera embodying a flash illumination system including a flash socket assembly implementing the teachings of this invention; a multilamp flash assembly adapted for connection into the socket assembly is shown exploded from the socket assembly for clarity of illustration;

FIG. 2 is a schematic view of a flash illumination system with which this invention is concerned;

FIG. 3 is a perspective view of a flash socket assembly incorporating the teachings of this invention;

FIG. 4 is a bottom view of the FIG. 3 socket assembly;

FIG. 5 is a bottom view of the FIG. 3 socket assembly similar to FIG. 4 but showing a printed circuit strip pulled back to reveal the underside of the socket body;

FIG. 6 is a side elevational view of the FIGS. 3-5 socket assembly, partially broken away;

FIG. 7 is a fragmentary perspective sectional view of the socket assembly shown in FIG. 3 as it would appear with the connector blade of a flash assembly inserted into the socket assembly;

FIG. 8 is a fragmentary sectional view taken generally along lines 8-8 in FIG. 3 as it would appear empty and with the contact members cut away;

FIG. 9 is a fragmentary sectional view taken generally along lines 9-9 in FIG. 3;

FIG. 10 is a fragmentary sectional view taken generally along lines 10-10 in FIG. 3 showing the socket assembly as it would appear when empty;

FIG. 11 is a view similar to FIG. 10 but showing the contact members as they would appear when a flash assembly is connected in the socket assembly; and

FIGS. 12-15 are views illustrating an alternative embodiment of the invention; FIGS. 12, 14, and 15 are views corresponding to FIGS. 7, 10 and 11; FIG. 13 is a fragmentary top view of the socket assembly.

DESCRIPTION OF THE PREFERRED EMBODIMENTS

This invention is in general concerned with an improved flash illumination system employing as its source of luminous energy a disposable multilamp flash assembly. FIG. 1 illustrates a flash assembly 10 of a type and construction as shown and described in the above-noted U.S. Pat. Nos. 3,598,984 and 3,598,985. The flash assembly 10 is shown as comprising a first linear array of lamps 12 and a second oppositely facing linear array of lamps 14. A support structure 16 supports the arrays of lamps 12, 14 and a relatively thin,

shallow connector blade 18 which extends downwardly therefrom and carries on opposite faces first and second sets of terminals for the lamps.

FIG. 1 shows the terminals as taking the form of a set of terminal strips 20 disposed in parallel along the direction in which the flash assembly 10 is inserted into a socket assembly. A similar set of terminal strips (not shown) on the opposite face of the connector blade 18 are electrically connected to the array of lamps 14 facing in the corresponding direction (rearward in FIG. 1).

The FIG. 2 schematic diagram illustrates a flash assembly 10 electrically connected to a flash selecting system 22 through a plurality of leads 24 which terminate in contact members 26 making engagement with terminal strips 20 on the flash assembly 10. As shown clearly in FIG. 2, six terminal strips are provided for the five lamps in each array. The sixth terminal strip, designated 20a in FIG. 2, is a ground terminal connected to a common ground wire for the lamps.

This invention is directed to the provision of an electrical interfacing system (shown schematically in FIG. 2) for interconnecting the lamps in a flash assembly with a flash selecting system. A full description of electrical interfacing systems according to this invention will be given below.

The flash selecting system 22, shown in black box form in FIG. 2, may take any of a variety of forms but preferably comprises a static electronic flash sequencing or programming circuit, as shown for example in the above-mentioned U.S. Pat. No. 3,618,492. A flash selecting system such as the system shown and described in the referent patent is capable of selecting a lamp or lamps in an operatively connected flash lamp assembly according to a predetermined sequencing or other selection program. A flash illumination system of the nature described has no moving parts, may be programmed with a wide range of flash selection programs, is capable of automatically avoiding defective lamps, and has many other advantageous characteristics, as pointed out in detail in the said patent.

As suggested above, flash illumination systems with which this invention is concerned have general utility in cameras of many types and constructions; however, apparatus according to this invention is perhaps most useful when embodied in compact cameras in which available space is at a premium. FIG. 1 shows a front portion of a folding camera 29 of a form disclosed in the above-noted patents held by the assignee of this invention U.S. Pat. Nos., 3,447,437; 3,543,662; 3,561,339; and 3,587,426. The FIG. 1 camera 29 is illustrated as comprising a front assembly 30 mounted to pivot into a face-down position on a back housing plate 32 when the camera is folded for storage. The front assembly 30 is shown as including an objective lens 34 having a picture-taking axis 35, a focus wheel 36 for focusing the lens 34, and a shutter actuator 38.

The front assembly 30 includes a flash socket assembly 40 embodying the teachings of this invention; the socket assembly 40 is shown in detail in FIGS. 3-11. A boss 42 on the socket assembly 40 extends through a top wall 43 of the front assembly 30 and defines an entrance slot 44 orthogonal to picture-taking axis 35 for receiving the connector blade 18 of a flash assembly 10. The boss 42 is also useful for its minimization of the amount of depth-wise space which the socket assembly 40 must occupy within the camera front assembly 30.

The socket assembly 40 is illustrated as comprising blade support means for receiving the connector blade 18 of a flash assembly 10 and for guiding the blade 18 into a predetermined operative position within the socket assembly. In more detail, the blade support means is illustrated as including rear support surface means, shown for example in FIG. 8 as a planar rear support surface 48, and opposed end support surfaces 50, 52. In the illustrated preferred embodiment the blade support structures constitute integral parts of a socket body 54 preferably composed of an electrically insulative plastic material. The socket body 54 preferably includes the boss 42 as an integral part thereof in which is formed the entrance slot 44. In order to facilitate connection of a flash assembly 10 into the socket assembly 40, the socket body 54 has formed therein an outwardly beveled mouth 56 surrounding the entrance slot 44. It is important that the depth of the mouth 56 be selected such that an adequate blade guiding function is performed without unduly reducing the purchase of the socket assembly upon a connector blade connected therein.

In accordance with the principles of this invention, contact means are provided for making electrical contact with terminals on the connector blade of a flash assembly 10, here shown as a set of terminal strips 20. The contact means are shown in this embodiment comprising a stationary set of rearwardly facing resilient contact members 46 arranged to engage the forwardly facing terminal strips 20 on a connector blade with a lengthwise wiping action when a connector blade 18 is inserted into the socket assembly 40.

The contact members 46 are preferably composed of a spring material having high electrical conductivity and high tensile strength such as certain well-known beryllium-copper alloys. A nickel-silver coating is preferably applied to minimize contact resistance.

In the illustrated FIGS. 1-11 embodiment, the contact members are illustrated as each including a terminal section 58, a curved section 60 adapted to be anchored in an opening in the socket body 54, a spine 62 extending upwardly from the base section 60, and a reverse-bent section 64 extending from the spine 62 downwardly along the direction of blade insertion for making operative electrical and mechanical engagement with a terminal strip 20 on a connector blade 18 inserted into the socket assembly 40.

FIG. 10 illustrates a contact member 46 as it might appear in its unstressed state. FIG. 11 illustrates the same contact member 46 as it might appear if deflected and stressed by a connector blade 18 inserted into the socket assembly 40.

FIG. 9 illustrates the rearwardly facing interior surface of the socket enclosure. In order to electrically isolate the contact members 46 from each other and in order to accurately position the contact members 46 in the socket assembly to insure registration with the terminal strips 20 on connector blade 18, the socket body 40 preferably has formed integrally therein a plurality of separated recesses 65, one for receiving each contact member 46. By this expedient the contact members are self-aligned in the socket assembly and the possibility of electrical shorting between the contact members 46 is minimized.

In the illustrated preferred embodiment the leads (shown schematically at 24 in FIG. 2) for connecting the described flash selecting system with the contact

members 46 preferably take the form of conductors 47 printed on a flexible sheet substrate 49 such as Mylar (TM). As shown with particular clarity in FIGS. 4-6, the printed circuit conductors 47 may be flow soldered to the terminal sections 58 of the contact members 46.

The flash selecting system preferably contains solid state circuitry fabricated in the form of an integrated circuit (I.C.) chip 51, the terminals 53 of which are connected to the conductors 47. Firing commands are supplied to the chip 51 through input/output terminals 55, also flow soldered to the conductors 47.

The printed circuit substrate 49 and the chip 51 carried thereby are preferably supported on an extension 68 of the socket body 54. The extension 68 defines a recess 49 for protecting the chip 51 and its terminals 53 and terminal connections. The extension 68 also serves as a convenient means for handling the socket assembly during fabrication thereof and during assembly into the associated photographic camera.

FIGS. 12-15 illustrate an alternative embodiment of the invention; FIGS. 12, 13, and 15 are figures corresponding to FIGS. 7, 10, and 11. The FIGS. 12-15 embodiment comprises a socket body 70 having blade support means including forward support surface means and rear support surface means. The forward and rear support surface means have facing end marginal portions 72, 73 and 74, 75, respectively, near the ends of entrance slot 76 for firmly engaging and supporting marginal end portions of the connector blade 18, designated 78, 80 in FIG. 5.

Considering the FIGS. 12-15 structure from another viewpoint, it can be seen that the rear support surface is recessed such that connector blade 18 is loaded against the rear side marginal portions 74, 75 thereby greatly relieving the tolerance requirements which otherwise would necessarily have to be maintained across the full width of the rear support surface.

The necked end portions of the entrance slot 76 (shown with particular clarity in FIG. 13) defined by end portions 72, 73, 74, 75 have a number of other important functions. Because the socket assembly is so extremely shallow, the working length of the contact members is necessarily extremely short. But in order to obtain the requisite blade loading forces, the contact members 100 must have a relatively high effective spring rate. A high spring rate and a short working length, however, implies a relatively limited deflection if overstressing of the contact members 100 is to be prevented. The necked end portions of the slot 76 act to limit pitching movement of the flash assembly 10 and thus control the stressing of the contact members 100 by connector blade 18. As will be explained in detail below, the novel configuration of the contact members 100 is such as to produce a relatively high blade loading without a correspondingly high actual spring rate in the contact members 100.

In order that the tolerance requirements may also be minimized in regard to the end-to-end dimensions of the blade-receiving space within the socket assembly, the FIGS. 12-15 socket assembly includes end support surfaces 88, 90 formed on lip portions 92, 94 below which are formed undercut surfaces 96, 98. By this expedient a connector blade is confined in its side-to-side movement by the end support surfaces 88, 90 only. The socket end-to-end tolerances in the FIGS. 12-15 embodiment must be held, then, only on the end support surfaces 88, 90.

To minimize contact of the endmost terminal strips 46 on a connector blade 18 with the socket body 70, in the FIGS. 12-15 socket assembly the maximum width $W_{c_{\max}}$ of each of the facing end marginal portions 72, 73, 74, 75 is caused to be less than the minimum width $W_{m_{\min}}$ of the marginal end portions 78, 80 of connector blade 18.

It is a stated object of this invention to provide a flash socket assembly including contact means interfacing with the terminal strips 20 on the connector blade of a flash assembly in such a way as to preclude misregistration of the contact means with the terminal strips, and thus to avoid an inadvertent firing of a non-selected lamp in the flash assembly. The connector blade 18 of a flash assembly adapted for use with socket assemblies according to this invention may be assumed to have a determinable minimum width " $Y_{\min}$ "; the terminal strips 20 may be assumed to have a determinable maximum width " $W_{s_{\max}}$ " and periodic spacing " P ".

To meet the above-stated object, the blade support means includes end support surfaces 88, 90 for engaging and confining opposite ends of a connector blade 18 received in the socket assembly. The end support surfaces 88, 90 are caused to have a maximum separation " $S_{\max}$ "; the contact members 100 are caused to have a predetermined maximum width " $W_{c_{\max}}$ " and a periodic spacing " P " equal to the spacing of the terminal strips 20. By this invention the maximum separation " $S_{\max}$ " of the end support surfaces 88, 90 is caused to be such that $S_{\max} - Y_{\min}$ is less than $P - W_{s_{\max}}/2 - W_{c_{\max}}/2$, thereby insuring that no misregistration of the contact members 100 with the terminal strips 20 on a connected flash assembly will occur.

It is another stated object of this invention to provide flash socket structures and contact means so configured and arranged as to preclude inadvertent simultaneous ignition of more than one lamp in a connected flash lamp assembly. To this end, the maximum width $W_{c_{\max}}$ of each of the contact members 100 is caused to be less than the spacing $P - W_{s_{\max}}$ between the terminal strips 20. By this expedient, at no time, and for no relative position of terminal strips 20 and associated contact members 100, may a contact member 100 bridge two terminal strips 20 and thereby cause a simultaneous ignition of more than one lamp.

The contact members 100 in the FIGS. 12-15 embodiment have a novel convolute configuration. The generally convolute configuration of the contact members acts to maximize the effective working length of the contact members 100 and the tolerable deflection of the contact members before overstressing occurs. The contact members 100 each comprise an end section 102, a base section 104 for connection to leads on a printed circuit substrate 106, a spine 108, and a reverse bent section 110. The reverse bent section 110 is illustrated as having an entrance ramp portion 112, a central portion 114, and an exit ramp portion 116.

The entrance and exit ramp portions 112, 116 assure a smooth, aesthetically pleasing insertion and withdrawal of the connector blade. The central portion 114 applies a loading force to the contiguous surface of a connector blade in a direction normal to the connector blade so as not to introduce any lifting force component which might tend to raise the connector blade from the socket assembly.

As noted above, it is desirable that the force required to insert the connector blade of a flash assembly into

the socket assembly is less than the force required to withdraw the connector blade. To this end, contact members are each configured such that upon insertion of a connector blade, the reverse bent portion 110 of the contact member offers a predetermined resistance to deflection and introduces a known frictional force against the blade. The net blade insertion force is caused to fall at a predetermined level or range of levels by an appropriate selection of the spring loading force applied by the contact members, the effective entry angle and configuration of the entrance ramp portion 112, and the coefficients of friction between the connector blade and the various surfaces which it engages during insertion into the socket assembly.

15 The withdrawal force is caused to be greater than this insertion force by virtue of a wedging action which is developed as the connector blade is withdrawn. It can be seen from a study of FIG. 15, for example, that as the connector blade 18 is withdrawn, as a result of frictional forces developed between the connector blade 18 and the reverse bent section 110 of each contact member 100, the reverse bent section 110 will be drawn along with the connector blade, thus causing the contact member 100 to unroll slightly. As the contact member unrolls, its diameter expands, causing a wedging or pinching action of the reverse bent section 110 against the end marginal portions 74, 75 of the rear support surface. By this expedient, the flash assembly 10, in spite of the extreme shallowness of the connector blade 18, is held securely against gravitational, centrifugal, impulsive, and other forces tending to dislodge the flash assembly from the socket assembly.

20 The contact portion 114 of each contact member 100 is caused to be as high as possible consonant with a reasonably shallow entry angle of the entrance ramp portion 112 in order that contact will be made with the terminal strips 20 on the connector blade 18 even in a situation wherein a flash assembly 10 is not fully inserted into the socket assembly.

25 30 35 40 45 50 55 As discussed above, it is desirable that the contact members 100 have a relatively low spring rate in order to minimize the likelihood of overstressing, and yet it is also desirable that the contact members 100 develop a relatively high blade loading force. To this end, contact members 100 include a tip section 117 extending from the reverse bent section 110 into engagement with the spine 108 to increase the effective spring rate of the contact members 100. By this expedient, a relatively great blade loading force can be developed in a contact member having a relatively low spring rate, thus minimizing the chance that overstressing of the contact members 100 might occur. Minimization of the spring rate of the contact members 100 is also advantageous in that the wear rate of the contact members 100 and thus the change in the spring rate thereof due to wear, are correspondingly minimized.

60 65 As discussed above, it is extremely important that contact resistance of the contact members 100 engaging the terminal strips 20 be minimized. Minimization of the contact resistance is achieved by virtue of the wiping of the terminal strips 20 by the contact members as a connector blade is inserted into the socket assembly, the wiping action serving to keep the terminal-contact member interfacing surfaces clean.

66 As described in some detail above, the contact members 100 not only function to electrically interface the flash assembly 10 with the flash selecting system 22,

but also serve to apply a loading force against the connector blade of a flash assembly inserted into the socket assembly. It is important that the blade loading force hold the connector blade 18 securely and stably against the above-described rear support surface acting as an alignment plane of reference.

However, the extreme shallowness of the connector blade 18, the radius on the free corners 118 and 120 of the blade, the radius "R" on the bottom edge of the blade 18, and the bevel depth "d" of the beveled mouth 122 surrounding the entrance slot 76 in the socket body 70 conspire against the achievement of a stable support for a connector blade against the rear support surface in the socket assembly. It can be seen that the primary constraint is the extremely limited blade depth "D" necessitated by the stringent space limitations imposed on the socket body 70 by the compactness of the associated photographic camera.

It can also be seen that the radius "R" of the bottom edge of the blade 18, necessary to facilitate insertion of the connector blade 18 into the entrance slot 76 and to eliminate sharp edges, reduces the blade area which may engage the end marginal portions 74, 75 of the socket rear support surface. The bevel depth "d" of the outwardly beveled mouth 122 also acts negatively to reduce the area of interface between the end marginal portions 74, 75 and the blade 18. The combination of these three primary factors severely restricts the ability of the blade loading means, here shown as the contact members 100, to hold the connector blade securely against the rear support surface provided by the socket assembly.

In accordance with an aspect of this invention, the contact portions 114 of the contact members 100 are caused to be aligned and to act on an inserted connector blade 18 in a longitudinally oriented force-receiving area on the blade having depthwise boundaries of $D-(R+d)$. By this expedient, optimum stability of the connector blade 18 in the socket assembly, and thus optimum stability of the flash array 10, is assured.

In order to allow presetting of the contact members so as to increase the blade loading forces developed thereby while assuring mutual alignment of the contact members even if unequally prestressed, the socket assemblies include limiter means for abutting the contact members to define a rearward limit position thereof. The limiter means takes the form of a wedge-shaped projection formed integrally with the socket body which engages the entrance ramp portions of the contact members. Other structures for accomplishing the desired limiting and aligning functions are contemplated.

The invention is not limited to the particular details of construction of the embodiments depicted, and it is contemplated that various and other modifications and applications will occur to those skilled in the art. Therefore, because certain changes may be made in the above-described apparatus without departing from the true spirit and scope of the invention herein involved, it is intended that the subject matter of the above depiction shall be interpreted as illustrative and not in a limiting sense.

What is claimed is:

1. A photographic camera including a lens having a picture-taking axis, a socket assembly for receiving and retaining a multilamp flash assembly having an array of lamps facing in a common direction and in the direc-

tion of said picture-taking axis and a supporting structure from which extends a connector blade carrying on a face thereof oriented in said common direction a set of spaced electrical terminal strips for the lamps in said array arranged in parallel along the direction of insertion of the flash assembly into said socket assembly, the blade being generally rectangular and of a depth "D" substantially less than its width "Y" with its bottom edge having a radius "R", said camera comprising:

means defining an entrance slot for the connector blade of the flash assembly which is perpendicular to said picture-taking axis of the camera, said entrance slot being surrounded by an inwardly beveled mouth of effective bevel depth "d";

blade support means for guiding the connector blade from said entrance slot into an operative position within said socket assembly wherein the face of the blade carrying the terminal strips faces forwardly in the direction of said picture-taking axis, said blade support means including rear support surface means adapted to be engaged by the blade for assisting in supporting the blade in said operative position;

contact means for making electrical contact with the terminal strips on the connector blade comprising a stationary set of parallel and rearwardly-facing resilient contact members arranged to register with and to engage the terminal strips with a lengthwise wiping action when the connector blade is inserted into said socket assembly, said contact members having aligned operative contact portions acting on the blade in a longitudinally oriented force-receiving area on the blade having maximum depthwise boundaries of maximum length $D-R$ and d which extend between d and R , as taken with respect to a blade fully connected in said socket assembly, such that the blade is held securely and with stability against said rear support surface means acting as an alignment plane of reference.

2. The apparatus as defined by claim 1 wherein said contact members each have a maximum width $W_{s_{max}}$ which is less than the minimum space between two adjacent terminal strips whereby engagement of more than one terminal strip by any contact member is precluded.

3. The apparatus defined by claim 1 wherein said contact members each include a base section for connection to a support surface at the bottom of a blade-occupying space within said socket assembly, a spine extending upwardly from said base section, and a reverse bent section extending from said spine downwardly along the direction of blade insertion for making operative electrical and mechanical engagement with a terminal strip on a connector blade inserted into said socket assembly.

4. The apparatus defined by claim 3 wherein said contact members each additionally have a tip section extending from said reverse bent section into engagement with said spine for increasing the effective spring rate of said contact members.

5. The apparatus defined by claim 1 wherein said blade support means defines opposed end support surfaces having lip portions, one adjacent and beneath each end of said entrance slot for engaging opposite ends of a connector blade received in said socket assembly, said end support surfaces being undercut below said lip portions to cause said end support sur-

faces to engage the connector blade only at said lip portions.

6. The apparatus defined by claim 1 wherein said contact members exert a predetermined loading on the connector blade received in said socket assembly producing frictional forces which are effective to retain the flash assembly securely in said socket assembly.

7. The apparatus defined by claim 1 including insulative spacing means for physically and electrically separating said contact members and for establishing and maintaining accurate alignment of said contact members with the terminal strips of the connector blade of a flash assembly inserted into said socket assembly.
